UNITED STATES PATENT OFFICE.

PRESTON E. GILLING, OF EAST ORANGE, NEW JERSEY.

ELECTRIC SWITCH.

1,101,272.

Specification of Letters Patent. Patented June 23, 1914.

Application filed November 3, 1911. Serial No. 658,347.

To all whom it may concern:

Be it known that I, PRESTON E. GILLING, a citizen of the United States, residing at East Orange, in the county of Essex and 5 State of New Jersey, have invented certain new and useful Improvements in Electric Switches, of which the following is a specification.

The present invention relates to certain 10 new and useful improvements in electric switches, the object of the invention being to provide a device of this character which embodies novel features of construction whereby it can be quickly rendered inoper- 15 ative so that the usual swinging of the switch arm will not operate to close the circuit, thereby preventing an unauthorized party from tampering with the switch and turning on the current.

20 A further object of the invention is to provide an electric switch which is comparatively simple and inexpensive in its construction, which can be readily manipulated in the usual manner to open and close the 25 circuit, and which can be easily and quickly rendered inoperative at any desired time without the necessity of using a special tool or actually disconnecting the wires.

With these and other objects in view, the 30 invention consists in certain novel combinations and arrangements of the parts as will more fully appear as the description proceeds, the novel features thereof being pointed out in the appended claims.

35 For a full understanding of the invention, reference is to be had to the following description and accompanying drawing, in which:—

Figure 1 is a top plan view of an electric 40 switch constructed in accordance with the invention, the handle or knob being applied to the switch arm so that by suitably swinging the switch arm the circuit can be broken and closed in the usual manner. Fig. 2 is 45 a top plan view of the switch with the handle removed so that the usual swinging of the switch arm will not operate to break and close the circuit. Fig. 3 is a vertical sectional view through the switch as shown 50 by Fig. 1. Fig. 4 is a similar view through the switch as shown by Fig. 2. Fig. 5 is an enlarged bottom plan view of the detachable knob or handle, and Fig. 6 is an enlarged side elevation of the detachable knob 55 or handle.

Corresponding and like parts are referred

to in the following description and indicated in all the views of the drawings by the same reference characters.

Specifically describing the present embodiment of the invention, the numeral 1 designates the switch base which may be formed of any suitable material, and is shown as hollowed out from the inner face thereof. This base 1 is provided with suitable openings 2 adapted to receive screws or similar fastening members for holding the switch in position. One side of the base is formed with an enlargement or boss 3 upon which one end of the swinging switch arm 4 is pivotally mounted, the said switch arm being formed of flat spring material and the opposite end thereof projecting over a rib or shoulder 5 formed with an inner curved face which is concentric with the axis of the 75 switch arm. In the present instance, this switch arm 4 is hinged upon a bolt or pivot pin 18 provided at the outer end thereof with a head 20, the said bolt passing through the switch base and having the inner end 80 thereof threaded for the reception of a nut 21. A washer 22 may be interposed between the switch arm 4 and the enlargement or head 3, and the pivot bolt 19 holds the swinging arm tightly against the top of the head 3 so that the free end thereof tends to swing downwardly against the shoulder 5.

85 A series of contact members 6, 7 and 8 are applied to the base 1 adjacent the inner face of the shoulder 5, the said contact members being formed with depressions 9 and also with stems 10 which pass through the base and are threaded for the reception of nuts 11, the said nuts serving as a means for holding the contact members in position. 90 One of the terminals of a circuit would be connected to the pivot bolt 19, while the opposite terminal of different circuits would be connected to the different contact members. It is preferred to connect terminals 100 to the end contact members 6 and 8 and to leave the intermediate contact member 7 free from any connections so as to provide a neutral resting place for the switch arm 4. This switch arm 4 is provided with a longitudinal slot 12 having the inner end thereof enlarged as indicated at 13, a key hole slot being thus provided which terminates at its outer end in a contracted portion adapted to be swung over the different contacts 6, 7 and 110 8. The handle or finger piece 14 is formed of some suitable insulating material and has

a contact stud 15 applied to the base thereof in some suitable manner as by means of the stem 16. This contact stud is formed with an intermediate contracted portion or stem 17, and also with a lower rounded portion or head 18 of such a size as to pass freely through the enlarged inner end 13 of the slot in the switch arm, while the contracted portion or stem 17 of the contact stud is of 5 such a size as to be received within the contracted portion 12 of the said slot. In order to apply the knob or handle to the switch, the head 18 is inserted through the enlarged portion 13 of the slot until the upper portion 10 of the head 15 contacts with the top of the switch arm, and the handle then moved outwardly to bring the stem 17 of the contact stud into the contracted portion 12 of the slot. When the knob or handle reaches 15 the outer limit of its movement, the lower rounded face of the head 18 can be swung into engagement with the depressions 9 of the several contacts. When the head 18 is in engagement with the middle contact member, the switch is in a neutral position, while 20 by swinging the arm to bring the head 18 into engagement with either of the end contacts 6 or 8, either of the circuits can be closed. The resiliency of the switch arm 4 tends to hold the head 18 in engagement 25 with the depressions 9 of the contacts, and the coöperation between these two elements holds the switch arm against accidental displacement, since a certain amount of force 30 must be applied to the switch arm in order 35 to move the head out of any of the depressions 9.

By reference to Fig. 4 it will be seen that the shoulder 5 projects upwardly away from 40 the switch base 1 farther than the contact members, and when the handle 14 is detached from the switch arm, the said switch arm is held out of engagement with the contact members and can be moved freely in 45 the usual manner without closing any of the circuits. When it is desired to leave the switch, it is merely necessary to slide the handle 14 to the inner end of the slot 12 and then lift the handle away from the switch 50 arm. The switch is then inoperative, the handle forming a small detachable unit which can be easily carried upon the person. This handle 14 and the contact stud 15 carried thereby being absolutely essential 55 to the successful operation of the switch, it will be obvious that when the handle is not in position it is impossible to close any of the circuits by merely swinging the switch arm. This handle, as has been previously 60 mentioned, constitutes a detachable unit which can be quickly placed in position or removed therefrom, and which is absolutely essential in order to successfully operate the switch and close any of the circuits.

65 I have shown in the drawings a plate of

sheet-metal 23 laid against the under side of the base 1, perforated to receive the stem 10 and pivot bolt 19 and clamped firmly to the base by nuts 11 and 21 on said stem and bolt, respectively. This plate 23 simply reinforces the base when the insulating material of which said base is composed is a little weak or brittle, and can be omitted without affecting the invention. Said plate of course does not reach to the stems or nuts of the end contacts 6 and 8, and if the middle contact is a neutral rest, as shown, it does not need to be insulated from the plate.

Having thus described the invention, what I claim as new and desire to secure by Letters Patent, is:—

1. A switch including a base, a swinging switch arm pivotally carried by said base, an arcuate shoulder at a distance from the pivotal mounting of said switch arm and providing a plane surface against which the outer end of the switch arm may rest, a contact member in the base and adjacent to the said shoulder and below the plane of its top whereby the switch arm is positively prevented from engagement with the contact member, a contact device, and interengaging means between said contact device and said switch arm whereby said contact device may detachably engage said arm to project therebelow and make electrical connection between the contact member and the switch arm.

2. A switch including a base, a switch arm pivotally mounted upon the base and formed with a slot having one end thereof enlarged, a contact member, means for holding the switch arm out of engagement with the contact member, a contact stud having an end small enough to be inserted through the large end of the slot of the switch arm and formed with a neck to fit into the contracted portion of the slot, the contact stud projecting below the switch arm to produce an electrical connection with the contact member.

3. A switch including a base, a swinging switch arm pivotally mounted thereon and formed with a slot having one end thereof enlarged, a contact member, a shoulder projecting from the base and serving to prevent the switch arm from engaging the contact member, a detachable handle, and a contact stud carried by the handle said contact stud being small enough to be inserted through the enlarged end of the slot in the switch arm and said contact stud being formed with a contracted portion to fit into the contracted portion of the slot.

4. A switch including a base, a switch arm pivotally mounted upon the base and formed with a slot having one end thereof enlarged, a contact member formed with a depression, a shoulder arranged under the switch arm to hold the switch arm out of

engagement with the contact member, and a detachable contact stud having one end thereof small enough to be inserted through the enlarged end of the slot and formed with a neck to fit into the contracted end of the slot, the said contact stud having a rounded end adapted to be seated in the depression of the contact member so as to produce an

electrical connection between the contact member and the switch arm when the neck 10 of the contact stud is in a predetermined position in said contracted end of the slot.
